COOLING SYSTEM OF INTERNAL COMBUSTION ENGINES

Kihachi Kato, Hongo-ku, Tokyo, Japan, assignor to Minato Tsuji, Tokyo, Japan

Application July 3, 1935, Serial No. 29,750
In Japan July 9, 1934

4 Claims. (Cl. 123—171)

This invention relates to the cooling system for an internal combustion engine cylinder, and more particularly to that type in which the engine cylinder is cooled by the air directly applied to the outside surface of the cylinder.

It is an object of the present invention to provide a novel cooling system which is reliable and efficient in operation and particularly adapted to insure suitable cooling under adverse conditions.

It is another object of the invention to provide a system which uses exhaust gas and compressed air which are conducted to the cylinder jacket for forced draft cooling and the air contacting with fins extending beyond the outside surface of the cylinder jacket for natural draft cooling.

It is a further object of the invention to provide such a device embodying a muffler which cools, and also silences the exhaust gas and allows it to expand.

The water jacketing system of cooling internal combustion engines is in many respects unsatisfactory and the air cooling system is to be preferred. There are however difficulties in the way of providing a satisfactory air cooling system.

A forced draft system requires power to drive the impeller of the blower to feed the cooling air and is moreover apt to reduce the temperature to too great an extent in winter. A natural draft system is found inadequate in that the cylinder is not sufficiently cooled.

Applicant's invention combines these two air cooling systems in a way to secure the advantages of both and eliminate their defects.

According to this invention the exhaust gases are cooled in the exhaust pipe and are used to cool the cylinder, a stream of compressed atmospheric air entering the exhaust pipe and assisting in said cooling of the engine.

By the combined system of natural and forced draft, the engine can be adequately cooled, avoiding overheating and overcooling, because as the load of the engine increases more exhaust gas will be delivered, and as the load of the engine decreases less exhaust gas will be delivered.

The invention may be carried into practice in various ways but one embodiment will be described by way of example with reference to the accompanying drawing, in which Fig. 1 is a somewhat diagrammatic side elevation partly in section of an internal combustion engine. Fig. 2 is a plan view of Fig. 1; Fig. 3 is a lateral

section of one cylinder; Fig. 4 is a plan view of one cylinder, the cylinder head being removed.

Referring to Fig. 1 of the drawing, there is shown the cylinders of internal combustion engine 1 which are cooled by air passing through the jacketed space or other conduits fixed to the cylinders. The exhaust manifold 2 leads to the cooling muffler 5 in which is inserted a central rod 3 surrounded by spiral plate 4 which is corrugated in the central portion and smooth on the outer portion and more particularly the end which is nearer to the exhaust manifold may be made acute for the purpose of reducing the back pressure of the exhaust gas. Any number of such plates in series may be used but in the drawing two are shown.

By means of such a muffler, the exhaust gas noise is reduced and the exhaust gas expands freely during its revolving motion and its temperature is reduced to such an extent that the expanded gas can be used for the purpose of cooling the engine cylinders effectively and reliably.

The cooled gas is then conducted to the cooling manifold 18 and then cylinder head 7'. The mixing device 6 is interposed between the muffler and cooling gas manifold 18. The air is compressed by the impeller 9 which is driven by step up gearing 8—8', the gear 8 is fixed to crank shaft of the engine and the gear 8' is fixed to the impeller shaft 9'. The compressed air is conducted by pipe 10 which has the valve 20 operated by the controlling rod 19. The mixing device comprises a jet 11 and of Venturi type construction 12. The gas mixed with the air is conducted to the cooling manifold 18 and is then directed about the cylinder head 7'. The cylinder jacket has ribs 14 as shown in Fig. 4 and forms many conduits 13 for the cooling gas. The ribs 15 outside of jacket 1 can be provided to assist the cooling. After cooling the cylinders, the gas collects in the space 16 and finally escapes through the exhaust pipe 17.

Having now particularly described and ascertained the nature of my said invention and in what manner the same is to be performed, I declare that what I claim is:

1. In an internal combustion engine, a cylinder, a cooling jacket surrounding said cylinder, an exhaust conduit leading from said cylinder to said cooling jacket, means in said conduit for cooling the exhaust gases, an air compressor and an air conduit from said air compressor leading into said exhaust conduit at a point between said cooling means and said cool-

ing jacket and an outlet from said cooling jacket.

2. The device as claimed in claim 1, wherein said cooling jacket has internal fins connected to said cylinder and external fins on its outer surface.

3. The device as claimed in claim 1, wherein a constriction is formed in the exhaust conduit and the compressed air conduit ends in a taper at said construction opening toward the cooling jacket.

4. In an internal combustion engine, a cyl-

inder, a cooling jacket surrounding said cylinder, an exhaust conduit leading from said cylinder and to said cooling jacket, means connected with said exhaust conduit for cooling the exhaust gases and means for admitting air into said exhaust conduit to mix with the exhaust gases, and means for compressing the air, the means for admitting said air to the exhaust conduit being so arranged as to add to the velocity of the exhaust gases.
